UNITED STATES PATENT OFFICE.

THOMAS I. POTTER, OF PORTLAND, OREGON.

KEY-CONTROLLED COIN-DELIVERING APPARATUS.

1,011,845.

Specification of Letters Patent. Patented Dec. 12, 1911.

Application filed February 28, 1910, Serial No. 546,187. Renewed October 25, 1911. Serial No. 656,721.

To all whom it may concern:

Be it known that I, THOMAS I. POTTER, a citizen of the United States, residing at Portland, in the county of Multnomah, State 5 of Oregon, have invented certain new and useful Improvements in Key - Controlled Coin-Delivering Apparatus; and I do hereby declare the following to be a full, clear, and exact description of the same, reference 10 being had to the accompanying drawings, forming a part of this specification, and to the figures and letters of reference marked thereon.

This invention relates to that type of coin 15 handling apparatus designed for delivering a single coin or a combination of coins to make up a predetermined amount of money, and is more especially designed for use in making payments of predetermined amounts, 20 such, for instance, as the payment of checks by the cashier of a bank, although it will be understood that I do not wish to be limited to this particular field of usefulness for the apparatus, inasmuch as it will be obvious 25 from the description of the machine that it may be used in various situations where it is desired to deliver a predetermined amount of money, register the amount so delivered and, if desired, record the amount delivered 30 at each transaction on the particular check or voucher which is given as a receipt for the money.

The machine may be said to comprise generally, a key-board, the keys of which are 35 arranged in groups, each group having a selector and each key of a group controlling the positioning of the selector and coin ejectors directly controlled by the selectors to eject and deliver coins of the proper value 40 in accordance with the key of the group which has been actuated. By providing a selector for each group of keys the necessity for permutation of the selectors is avoided and the operating mechanism correspond- 45 ingly simplified.

The machine further comprises a registering mechanism controlled by the selector positioning and ejector operating mechanisms and adapted to register the amount 50 delivered by the machine whereby the total of the deliveries may be known without computation and, if desired, compared with the amounts on the receipts or vouchers given for the amounts delivered.

55 The machine further comprises a printing mechanism operated by the selector post-

tioning mechanism whereby printing characters for recording the amounts delivered by the ejectors at each transaction will be brought to a printing position in proximity 60 to a supporting table or ledge upon which the check or receipt may be positioned for receiving the impression, the impression being made by a platen suitably actuated substantially simultaneously with the actual delivery of the coins by the ejecting mechanism. 65

The ejector operating mechanism and impression devices are so connected that when one is operated, the other is invariably operated and the support for the check or receipt is so positioned that the person making payment may conveniently locate the check or receipt for receiving the impression without interfering with his manipulation 75 of the machine or the handling of the coins delivered.

While the machine comprises the groups of elements all correlated in the manner just set forth, it will be understood that each 80 group, although it does, in fact, comprise elements entering into and forming a part of the other groups, may, nevertheless, have a field of usefulness quite distinct from the particular machine about to be described 85 and the present invention is intended to comprehend said mechanisms either individually or collectively.

Referring to the accompanying drawings—Figure 1 is a front elevation of a key 90 controlled manually operated coin delivering apparatus embodying the present improvements, the casing being removed and parts broken away in order to show the remaining parts on a large scale. Fig. 2 is a sectional plan of the machine illustrated in Fig. 1 with parts broken away. Fig. 3 is a section taken mainly in a horizontal plane longitudinally of the axis of the selector plates and showing in sectional elevation parts lying 100 below that plane. Fig. 4 is mainly an end elevation with the casing and operating handle removed but with the keyboard in section to illustrate the construction and arrangement of the keys. Fig. 5 is a sectional 105 elevation showing one group of keys, the selector positioning mechanism and the printing mechanism. Fig. 5^a is a detail perspective view of the operating arm on the impression mechanism or platen. Fig. 110 5^b is a plan view of the pawl for coöperating with the arm shown in Fig. 5^a together.

with the hub of the operating lever on which said pawl is mounted. Fig. 6 is a sectional elevation substantially on the line 6—6, of Fig. 2. Fig. 6^a is an elevation of one of the ejectors. Fig. 7 is a sectional elevation in a vertical plane illustrating more particularly the printing mechanism in its normal position, this view differing from Fig. 5 in that in Fig. 5 the printing mechanism is shown partially actuated. Fig. 8 is a plan and Fig. 9 is a front elevation of one of the zero stops. Fig. 10 is an elevation of one of the sections of the main frame showing the bearings for the main operating shaft, the telescoping selector shaft and the slide ways for the coin ejecting mechanism. Fig. 11 is a side and edge elevation of one of the sections of the operating frame for moving the arms which control the positions of the selectors and the operation of the registering and printing devices. Fig. 12 is an elevation of one of the key retaining and releasing slides, there being one of these slides for each group of keys. Fig. 13 is a sectional elevation showing the operating connections for the registering mechanism, other parts of the mechanism being omitted in order to avoid confusion. Fig. 14 is an elevation looking at the rear side of the mechanism shown in Fig. 13, the fixed frame or supporting parts being omitted. Fig. 15 is a detail elevation for illustrating particularly a part of the carrying devices for the registering mechanism. Figs. 16 and 17 are corresponding elevations showing a part of the carrying mechanism in different positions assumed by it in operation. Fig. 18 is a top plan view of parts illustrated in Figs. 15, 16 and 17. Fig. 19 is a top plan view of the registering wheels and their operating rack bars. Fig. 20 is a side elevation of the full stroke device preferably employed in connection with the operating handle and Fig. 21 is a section on the line x—x₁ of Fig. 20. Fig. 22 is a diagrammatic sectional elevation corresponding in some respects to Fig. 6, but showing a modified arrangement of the connections between the lever and the ejectors. Fig. 23 is a detail top plan view of certain of the parts shown in Fig. 22 and Fig. 24 is an edge elevation of the connecting link or lever interposed between each ejector and its control plunger.

Referring more especially to Figs. 1, 2 and 3 of the accompanying drawings which show the general arrangement of the mechanism in the preferred type of machine it will be seen that there is employed a series of coin stacks or receptacles A arranged at the top and front of the machine while at the right hand end of the machine there is a small compact key-board B having five rows or groups of keys with nine keys in each row or group. There is also at the

right hand end of the machine an operating handle C and in front and below the coin receptacles a chute or hopper D for guiding the coins ejected from the receptacles down to a common receiver D' from which they may be conveniently removed by hand. 70

In order to simplify the mechanism as far as practicable and to secure greater accuracy in the results the coin stacks or receptacles are divided into four groups or sections indicated in Fig. 2 and each section or group has its own selector plate adapted to be moved into position when the operating handle is manipulated but the operative position of which is established by the keys of its own group of keys in the key-board. 75 As shown, the right hand group of keys establishes the position to which the left hand selector plate shall be moved; the second group of keys establishes the position 80 for the selector plate of the second section; the third group establishes the position for the selector plate for the third section; the fourth group establishes the position for the fourth section, and the fifth group controls the registration and printing mechanism for higher amounts than can be conveniently handled by the coin stacks or 85 holders, and, therefore, does not control a selector plate. 90

Conveniently, the selector plates referred to are in the form of segments E (Figs. 3 and 6) carried by frames E' rigid on the ends of tubular shafts E². The tubular shafts E² are arranged one within the other 95 but are of different lengths whereby the respective selector plates may be mounted on their exposed ends and in alignment with each other.

At their opposite ends each shaft is provided with an arm F rigid with the shaft and each arm is provided with a gear segment f (Fig. 13) for operating the registering mechanism, as will be presently described, and a link connection f' (Figs. 5 and 7) for setting the printing mechanism as will be hereinafter described. The arms F are so positioned and formed that their outer ends may be swung in the arc of a circle each substantially in the plane of the group or column of keys for controlling the position of the selector plate connected therewith. 110

In the preferred construction the arms F are positively swung or moved in both directions through connections with the operating handle and when they arrive in position for co-operation with an operated key they are locked to said key and the connection between the arm and operating handle is interrupted leaving the arm locked to the key until such time as it is to be returned to its normal position. 115

By reference particularly to Figs. 4 and 5 it will be seen that the keys are arranged 120

in the key board with their inner circular or knob-like ends b in the arc of a circle. Said keys are mounted to slide in plates B' and are normally held outwardly by springs b' . Each group of keys works through a retainer and release plate or segment B^2 shown in detail in Fig. 12 and each key is provided with a projection b^2 having oppositely inclined faces and a shoulder for co-operation with the retainer and release plate. Said plate is normally held up by a spring b^3 , Fig. 4, and upon the operation of any key of a group it is depressed by the projection until the projection passes the plate when the plate engages the shoulder on the projection and holds the key in its operated position, as illustrated in Fig. 5. The operation of any other key of the series will release the key first operated and result in the retention of the key last operated, whereby but one key of a group will be held in operated position by the retainer plate.

When a key of a group is operated its inner end is projected into position for co-operating with the locking devices for the arm F of that group, and said locking devices together with the arm operating mechanism are as follows: Journaled on the telescoping shafts between each of the arms is an operating disk G (the end disk being shown in detail in Fig. 11) and said disks are all connected together by a bolt G' working through slots in the segmental portions of the respective arms. The disks are spaced apart by sleeves g , Fig. 11, surrounding the bolt, whereby friction between the disks and arms is avoided and the disks connected rigidly to operate as a unitary body. Each disk is provided with a notch or recess g' and a shoulder or projection g^2 , together with a concentric face g^3 , which parts co-operate with parts carried by the respective arms F . Each arm F is provided with a longitudinally movable locking pawl g^4 adapted to enter the recess g' in its disk or to ride on the concentric face g^3 while the arm is locked to a key. At its outer end each longitudinally movable pawl g^4 is pivotally connected with a latch g^5 pivoted on the end of the arm F and adapted to swing in the arc of a circle. The outer face of the latch is provided with a recess g^6 , Fig. 4, adapted to engage and embrace the rounded ends of the keys, thus, with the parts in their normal position, as shown in Fig. 4, where the pawl is in engagement with its notch in the disk, if said disk be turned to carry the arm up to either of the positions indicated in Fig. 5, the said recess g^6 will receive the rounded end of the key and thereby swing the latch into a position where the key and arm will be locked together; the pawl will be withdrawn from the recess in the disk and further movement of the disk will, by the engagement of the concentric

face with the inner end of the pawl, prevent the disengagement of the latch and key until such time as the disk is brought back into position for the pawl to enter the recess.

Assuming that the disk and pawl are in the position last mentioned, reverse pressure on the arm will effect the disengagement of the latch from the key and a return of the latch and arm to normal position. To effect this result each disk is provided with the shoulder g^2 hereinbefore mentioned which, in the machine illustrated is adapted to contact with one of the pawl guiding projections g^7 on the arm.

The operating disks G are moved as a unit by a link connection or connections J with an operating arm or arms J' keyed to the shaft J^2 which carries the operating handle C . The shaft is adapted to be oscillated by said handle so as to make a complete excursion forward and back through a definite angle greater than the required movement of the arm and sufficiently great to effect a double movement of the operating disks throughout a portion of their excursion, the excess movement being utilized to operate the ejectors for ejecting the coin whereby all of the active operations of the machine are performed during the movement of the handle in one direction, the resetting of the parts only being effected during the reverse or return movement of the handle. If no key of a group has been operated for arresting the arm of that group, it is obvious that said arm would make a full excursion with the operating disk, whereas it is desirable that the arms should be arrested during the initial portion of their movement if no key of the group has been operated. To perform this function, a device which may be conveniently termed a zero stop, is employed. This zero stop consists primarily of a pawl H , Figs. 4, 5, 8 and 9, pivoted to swing laterally on a vertical axis h in the frame and having a rounded end normally occupying a position which corresponds to the position of an operated key at the zero point, the zero point, however, being a point to which the arms would be moved by a slight angular movement of the operating disk and will bring the selector plates into a position where they form a barrier to prevent the advance of the ejectors for that group.

By reference to Figs. 8 and 9 it will be seen that the zero stops or pawls H for each group of keys are each provided at its rear end with an incline H' normally in position to be engaged by a pin or roller h' on the key retaining and release plate B^2 whereby, when said plate is depressed by the operation of a key, the said roller strikes the incline H' and swings the zero stop laterally out of the path of the arm and latch carried thereby. To retain the zero stop in

its lateral position against the tension of the spring h^2 normally tending to return the same to its operative position, the said zero stop is provided with a transversely arranged spring pressed pawl h^3 , the end of which is adapted to engage the side face of a lever I when the stop is moved transversely, as shown by the dotted lines in Fig. 8. The lever I forms one arm of a bell 10 crank lever, the other arm I' of which is connected with a release key I² whereby the zero stop may be manually released at any time should it be desired to return the same to its normal operative position as, for instance, if a mistake has been made in operating the key of any particular group and it is desired that no coin shall be ejected by the mechanism controlled by that group or, in other words, if it is desired to cancel the 15 effect of operating any key in the group. The lever I is further utilized as a portion of the means whereby all of the keys and the zero stop are automatically released by the return of the arm to its normal position 20 shown in Fig. 4 and for this purpose a rocking frame having a front bar and side levers I³ is provided with a pawl i⁴ adapted to engage a pin i⁴ on the lever I. The rocking frame I³ is provided with a spring i⁵ 25 normally tending to elevate the same in position for the pawl to engage with the pin i⁴ but the front bar of the frame I³ is in position to be engaged and depressed by the latches g⁶ on the arms F when the latter 30 return to their normal position. The downward movement of said lever I pushes the frame down and with it the key retaining and release plate B², inasmuch as the lower end of said plate is curved around and 35 forms a hook to engage with the pin i⁴, as shown at i⁶. Just as the parts reach their normal positions the pawl i⁴ is released from its engagement with the pin i⁴ by contacting with a fixed pin i⁷ (indicated in dotted 40 lines in Fig. 4) whereby the lever and the key retaining and release plate are allowed to assume their normal positions and all operated keys will have been released.

The oscillatory shaft to which the handle 50 is connected, preferably extends through the machine from end to end and is adapted to operate the coin ejecting mechanism, the ejecting of the coins, however, taking place only during the final portion of the forward 55 movement of the handle, the initial or first part of the movement of said handle being utilized, as before stated, for positioning the selector plates and locking the same in their adjusted positions, as well as for performing certain other functions to be hereinafter described. The ejector mechanism is operated by said shaft during the final portion of its forward movement through instrumentalities which are preferably as follows: At suitable points on the shaft, pref-

erably at each end and midway of the length of the group of selector plates, arms K (Fig. 6) are rigidly mounted on the shaft. In proximity to said arms, the shaft carries levers K', each provided with a slot k in which works a pin k' on the arm K. The length of the slot is such that during the first portion of the movement of the shaft the pin plays idly in said slot but contacts with the rear end of the slot so as to move the arms K', when the selector plates have been properly positioned, further movement of the shaft in the same direction serving to impart an operative forward movement to the arms K' and through them the ejector-mechanism is operated. The arms K' at their upper ends are pivotally connected with links l adapted to embrace the ends of bars L mounted to slide in ways M (Fig. 10) in the frame. Below the bars L and connected thereto by suitable bolts or posts are bars L', the latter also working in openings in the frame indicated at M' in Fig. 10. The links l are provided with openings for the ends of the bars L, of sufficient size to permit of the necessary angular movements of the links during the swinging of the levers K' and when said levers are moved the bars will be drawn forwardly in the ways of the frame to operate the ejectors. Said ejectors are indicated in Figs. 2, 6 and 6^a by the letter N.

The ejectors are each formed by a relatively thin blade or bar suitably mounted in the frame so as to slide longitudinally and 100 to intersect the bottom of the coin stacks and eject the coins. The connections between the bars L and ejectors are preferably formed as follows: The bars L pass through slots N' in the ejectors and may 105 travel back and forth in said slots. Said bars L' carry springs l' adapted to engage with the rear ends of the ejectors so as to advance said ejectors with the bars, but if the movement of the ejectors be arrested 110 the springs will ride out of their seats and permit the ejectors to remain stationary while the bars complete their excursion. Additional connecting means are also preferably provided in the form of pawls which drop in behind projections on the ejectors 115 after the latter have passed through the selector plates, thus insuring a positive connection between the bars and ejectors at the time when the coins are to be engaged 120 and discharged from the stacks. Conveniently, each frame is provided with guide ways having inclines m thereon located at a point slightly in rear of a position which would be reached by a projection N² on the 125 ejectors when the forward ends of the ejectors have passed through the selector plates. Pawls O loosely hung on the upper ends of the posts O' are guided by the inclines m so as to drop in behind the projections N² 130

when the ejectors have advanced to the point before stated, but if said ejectors are arrested by the selector plates the pawls O will pass down in front of said projections and will then travel forward with the bars $L-L'$ without carrying the ejectors with them. The operation of this portion of the apparatus will be readily understood from Fig. 6 wherein the ejectors, pawls, and springs are shown in full lines in their normal or inoperative position and in dotted lines in their forward position after a coin has been ejected from the base of the stacks. Inasmuch as the shaft J^2 has a range of movement greater than the arms K' and the ejectors should be returned to their normal positions during the first portion of the return movement of the shaft J^2 to withdraw the ejectors from the selector plates before the latter begin their return movement, provision is made for connecting the levers K' and arms K during initial return movement of the shaft. The connections preferably employed embody hook pawls k^2 pivotally mounted on the levers K' and adapted to engage the ends or shoulders k^3 on the arms K when the latter are moved to the position indicated in dotted lines in Fig. 6, or at the time when the levers K' begin their forward movement. The pawls k^2 serve to connect the arms and levers throughout the remaining portion of the forward movement and during the initial portion of the reverse movement, but are disengaged from the arms by contact with adjustable screws or stops k^4 in the frame, when the levers K' have returned to their normal positions. The arms K , however, continue their return movement, and during this portion of their movement the selector plates are returned to their normal position through their connections with the arms F before described.

The sequence of operations just referred to will, perhaps, be best understood by reference to Figs. 4 and 5 in connection with Fig. 6. In Fig. 5 the lever arm J' is shown in full lines in the position it occupies when the selector plates have been positioned and the pin k' has reached the end of the slot k in the arm K' . From the position indicated in full lines in Fig. 5 to the position indicated in dotted lines, the lever arm J' and shaft J^2 on which it is mounted is completing the final portion of its forward movement and is effecting the operation of the ejectors to eject coins from those coin stacks with which the proper apertures in the selector plates are brought into alignment. This movement of the lever arm J' from the position shown in full lines to the position shown in dotted line will result in a retrograde movement of the operating disks for the arms F but, inasmuch as said disks have been moved forwardly a greater distance

than was necessary the retrograde movement does not bring the disks into engagement with said arms F . In addition to their function of positioning the selector plates E , the arms F also operate in conjunction with the lever arm J' to set and operate both the registering mechanism and the printing mechanism, the connections for operating the printing mechanism being substantially as follows: A series of segments P bearing suitable numerals on their peripheries are pivotally mounted on a shaft p hung in the frame preferably immediately below the front portion of the keyboard. The segments P may be conveniently termed type segments as each carries numerals corresponding to the numerals indicated by the keys of its particular group and each is connected by a link $p'f$, with the arm F of that group of keys. The link connection p' is made adjustable at p^2 for initially setting the type segments and it is obvious that when the arms F are swung to their proper positions for locking the selector plates, the type segments P will be correspondingly swung so as to bring the desired character to a definite point which may be termed the printing point. In Figs. 4 and 7 the parts are shown in their normal positions, while in Fig. 5 the arm F of one group of keys has been swung into engagement with the third key from the bottom. This has positioned the proper selector plate and has also positioned the type segment for that group of keys so as to bring the proper numeral to the printing point. During the movement of the arm F to the position indicated, the lever arm J' has moved to the full line position in Fig. 5 and has thereby depressed the platen or hammer P' against the tension of an elevating spring P^2 . The connections whereby the platen P' is depressed, preferably consist of an arm p^3 on the stem of the platen, Figs. 5 and 5^A, and a laterally swinging pawl p^4 , Figs. 5 and 5^B, on the lever arm J' . The arm p^3 is provided with an incline p^5 adapted to deflect the pawl p^4 laterally during the return movement of the lever arm, but said pawl p^4 , during the forward movement of the arm from the position indicated in full lines to that indicated in dotted lines, will first depress and then ride off the top of the arm p^3 , thereby releasing the platen or hammer P' and the latter, under the influence of spring P^2 will strike a blow on the under side of any paper or impression surface which may be interposed between it and the type at the printing point.

In accordance with the present invention, it is designed that the check, receipt or voucher given for the coin discharged from the machine, shall receive the impression of the characters indicating the amount of money discharged and to enable the said check, voucher or receipt to be conveniently

and properly inserted, a suitable table or support P^3 is arranged in proximity to the printing point or in such relation thereto that the check, voucher or receipt may be slipped beneath the type segments for receiving the impression. In order that the platen or hammer shall not obstruct the entrance of the check, the said hammer is normally supported, as shown in Fig. 7, so as to leave a space between its face and the face of the type at the printing point. It may be held down to the position desired by a supplemental spring P^4 acting against the tension of the spring P^2 or, as is obvious, the spring P^2 may be of proper length to normally support the hammer at the desired point, but the momentum of the hammer or platen is always sufficient to carry it beyond its normal point of support and give the desired impact against the rear face of the paper at the printing point.

For supplying ink to the type faces a roller P^5 is journaled in arms P^6 pressed upwardly by a spring P^7 . For renewing or re-inking the roller the arms P^6 may be depressed by a handle P^8 extending out at the end of the machine, and the roller itself may be withdrawn through an aperture in the end of the machine normally closed by the head or finger piece P^9 on the end of the roller (see Fig. 3).

Owing to the necessity of providing for various movements of the parts portions of which movements only are utilized in the manipulation of certain parts of the machine, the operation of a registering mechanism by the movement of the operating handle makes it desirable to employ a special form of registering mechanism in order to insure a correct registration of the coins ejected or discharged from the coin stacks. In other words, the registering mechanism must be so combined and related to the positioning of the selector plates and the operation of the ejectors that certain parts of the movements of the operating handle or shaft may take place without causing any movement of the registering mechanism and without liability of causing a false or incorrect registration under any possible manipulation of the machine.

In the preferred registering mechanism the registering wheels carry upon their peripheries numerals for indicating the totals of the amounts registered. They are ordinary indicating wheels Q journaled on a shaft mounted in the frame preferably at a point above the key-board so as to expose their peripheries at the reading point in a convenient position for observation by the cashier or person manipulating the machine. The primary registering wheels Q are five in number, one for each group or vertical column of keys and, in addition, there are preferably employed two additional register-

ing wheels Q' (Fig. 19) for registering amounts beyond the capacity of the primary registering wheels. Ordinary carrying mechanism, such as star wheels q and pinions q' may be employed for carrying from the last primary registering wheel Q to the secondary registering wheels Q' and particular description of this portion of the mechanism is thought to be unnecessary, as it is well known. The shaft Q^2 on which the registering wheels Q are journaled, also carries a swinging frame or hanger Q^3 in which is journaled a series of gear wheels q^3 meshing with pinions q^2 connected to the respective registering wheels Q . The swinging frame Q^3 is adapted to be swung about the shaft Q^2 as an axis whereby the gear wheels q^3 may be moved into or out of mesh with vertically arranged rack bars R mounted in ways r (Fig. 13) in the frame of the machine. The movement of the swinging frame or hanger Q^3 and gear wheels q^3 is controlled by a vertically movable rod S having at its upper end a slot or inclined guideway s' (Fig. 15) in which works a roller or bearing s^2 on the swinging frame Q^3 . Downward movement of the rod S will throw the gear wheels q^3 out of mesh with the racks R and upward movement of rod S will throw said wheels into engagement with the racks. At its lower end the rod S is pivotally connected to a lever s and is held in its upper or lower position as the case may be, by a spring s^3 . It is adapted to be moved into one position or the other by adjustable screws or operating projections s^4 , one mounted on the lever arm J' and the other mounted on a second arm J^3 rigid with the arm J' . The construction is such that when the arm J' is down in its normal position, as shown in Figs. 4 and 13, the screw s^4 in the arm J' will have moved the rod S upwardly and thereby thrown the gear wheels q^3 into mesh with the racks, but when the said lever arm J' has moved upwardly to the position indicated in dotted lines in Figs. 5 and 13, the projection on the supplemental arm J^3 will have engaged the lever s , thereby moving the rod S downwardly to disengage the gear wheels and racks and leave the registering wheels disconnected from their operating connections during the return movement of the lever arm J' .

The operative or downward movement of the operating racks R is derived indirectly in part from the arms F , and for this purpose, the gear segments f before referred to as a part of the arms F are each in mesh with a vertically movable rack bar R' and a pin r' on the upper portion of each of the rack bars R' works in a slot r^2 in the lower portions of the rack bars R . The pins and slots constitute loose connections between the two rack bars and the length of each

slot is such that the pin reaches the lower end of the slot when the arm F has been turned up to the zero position indicated in dotted lines in Fig. 5. A continued movement of the arms F will draw the rack bars R downwardly in proportion to the distance the arm F is allowed to move and the movement of the arm F, as before explained, depends upon which one of the keys 5 in the group has been operated. As the operating handle completes its forward movement and after the lever arm I has moved past a position where it can further operate arms F, the rod S is drawn downwardly, as 10 before explained, thereby disconnecting the gear wheels q^3 from the rack bars and the return movement of the rack bars may take place without affecting the registering mechanism. During the movement or that portion 15 of the movement when the registering wheels are being operated, it will be noted that each of said wheels is connected with its operating arm F and, inasmuch as it is only during the movement period, that 20 the carrying of a number from one wheel to that of the next higher denomination can be effected, the ordinary or previously known carrying mechanisms are not adapted for use in the present machine, but a very 25 simple and effective carrying mechanism may be employed which depends for its operation upon the loose connection between the two rack bars with means controlled by registering wheels of smaller denomination 30 for moving the upper rack bar R an increased distance when carrying from one wheel to the other is to be effected. This carrying mechanism, best illustrated in Figs. 13 to 18, inclusive, embodies a series of vertically arranged crank shafts, one for each 35 registering wheel, journaled in the frame and each crank shaft having two cranked portions T and T' respectively. The cranks T' project up in proximity to the registering 40 wheels Q and are adapted to be engaged by pins t on said wheels whereby the crank shafts will be swung on their axes at the time when the registering wheels are turned from the highest number to the lowest number 45 indicated thereby.

The cranks T of the crank shaft are relatively long and extend parallel with the rack bars in proximity thereto both above and below the meeting ends of said bars. 50 Said cranks T are adapted to engage rollers t' on carrying pawls or latches T², said carrying pawls or latches being pivotally mounted on the pins r' connecting the rack bars. At their upper ends, the carrying 55 pawls or latches are provided with inclines t² adapted to engage projections or rollers t³ on the upper rack bars R.

The operation of the carrying mechanism will now be readily understood and is as

follows: Assuming that the parts are in the 65 position illustrated in Fig. 16 and the registering wheel controlling the crank T, in this figure, is about to move from the highest number thereon to the lowest, or to pass the decimal point. As the rack bars move 70 downwardly, the crank T will be swung from the position indicated in Fig. 16 to the position indicated in Fig. 17, and the incline t² contacting with the roller t³ will draw the rack bar R downwardly an increased distance sufficient to advance the wheel, operated by the said rack bar one number and this movement will be in addition to the normal movement imparted to the rack bar R by the rack bar R'. The 75 pin t having moved out of engagement with the crank T' the said crank is free to return to its normal position and upon upward movement of the rack bars the end of the carrying pawl or latch t² will contact with 80 a fixed incline t⁴, shown in dotted lines in Figs. 16 and 17, thereby disengaging the carrying pawl or latch from the roller t³ and restoring the parts including the crank 85 and to their normal positions.

In Fig. 18, the rack bars have been omitted, but one crank shaft T, T' is shown in its normal position in full lines (Fig. 16) and in its operated position (Fig. 17) in dotted lines, together with the carrying pawl T² and the projections having inclines t⁴ thereon, all as viewed from above.

From the foregoing description it is obvious that the operating handle should invariably make a full stroke or movement in 100 each direction and to insure this result the hub of said handle or the shaft J² to which the handle is connected is provided with a full stroke mechanism shown in detail in Figs. 20 and 21 and partly in dotted and full 105 lines in side elevation in Fig. 4. A clutch segment V is keyed on the shaft or hub of the operating handle in position for its periphery to coöperate with spaced and oppositely arranged rollers or friction clutch 110 members v. Each clutch member v is loosely supported on the frame of the machine in position to grip the periphery of the segment V, one being adapted to grip the segment and prevent its movement in one direction and the other to grip the segment and prevent its movement in the opposite direction. In order to hold these clutch members out of engagement alternately during the movement of the shaft and operating handle in one direction or the other, a clutch release segment V' is journaled on the shaft and provided with clutch member engaging arms v', so spaced with relation to the clutch members, that when one clutch releasing segment the other is free to act, and vice versa. The clutch releasing segment is op-

erated by a pin W on the clutch segment V adapted to strike one or the other of a pair of adjustable screws or projections w on the clutch releasing segment and to move said 5 segment in one direction or the other when the operating handle reaches the extremes of its movement. For holding the clutch releasing segment in one position or the other, it is provided with a projection having inclined faces Y adapted to engage a 10 roller y on a spring pressed lever $\bar{Y}$, the arrangement being such that the crest of the projection moves past the roller in one direction or the other and the pressure of the 15 roller maintains the clutch released segment in the position to which it has been moved. With the parts in the position illustrated in Fig. 20 the upper clutch member v is held out of operative position, while the lower 20 one is in engagement with the periphery of the segment V and consequently the segment V may be moved and the shaft J^2 rotated in the direction indicated by the arrow, but reverse movement is prevented until the 25 clutch release segment has been shifted by the contact of the pins W with the lower set screw w , so as to release the lower clutch member and allow the upper clutch member to drop into its operative position.

30 In the modification illustrated in Figs. 22 to 24, inclusive, the levers K' , before described, at their upper ends are connected by an operating bar or rod indicated by the numeral 1 which bar passed through elongated slots 2 in a series of links 3 each pivotally connected at its lower end with an 35 ejector 4. The upper ends of the links 3 are pivotally and preferably loosely connected with the rear ends of ejector control plungers 5, which control plungers are, as shown, in Fig. 23, preferably offset or in a different vertical plane from the ejectors with which they are connected. The loose connection between the links 3 and control plungers 5 40 may be conveniently formed by a pin and slot connection 6 and the forward ends of the plungers 5 may be conveniently guided by transverse rods or guides 7 whereby said forward ends are in position in proximity 45 to the path of the selector plates or segments. With the construction described it is obvious that if a selector plate be interposed in front of the ejectors and ejector control plungers and an aperture in said plate or segment is 50 to line with one or the other of said members, a forward movement of the lever K' will cause the member in line with the aperture to advance while the other member will be arrested by the ejector plate. With this 55 arrangement the apertures in the plate are so located and positioned that an aperture will be in front of the ejector and no aperture will be in front of the plunger or when an ejector is not to be operated the op-

posite condition prevails, i. e., no aperture is 65 brought into position in front of the ejector but an aperture is brought into position in front of the plunger. This construction avoids the necessity of employing a separable connection with the lever K' and provides a connection whereby the ejectors will be operated positively or permits them to remain in inoperative position when no coin is to be delivered.

The coin stacks or receptacles are properly arranged in connection with the selector plates corresponding to the four groups or columns of keys thus, in the first section of the coin stacks there should be arranged three stacks for pennies and one stack for 70 nickels. The ejector for one of the penny stacks is arranged to discharge two pennies. From this section amounts up to nine cents may be discharged, one cent being delivered 75 when the first ejector alone is operated, two cents when the first and second ejectors are operated, four cents when the first three 80 ejectors are operated, and five cents when the last ejector is operated. In the second section the first coin stack is adapted to hold 85 nickels, the second and third dimes, the fourth quarters, and the fifth fifty cent pieces. With this construction it is possible 90 to eject any amount in five cent increments up to ninety cents by a proper arrangement 95 of the ejector apertures in the selector plate or segment. The other sections of the coin stacks and the ejectors and selector plates for use in connection therewith are arranged for ejecting larger amounts, or coins of 100 higher value, in increments which may be arranged to meet commercial conditions as will be readily understood.

The coin stacks are in a single row set on the frame of the machine so as to be easily 105 removed for the substitution of other stacks and occupy a slightly inclined position. They may be simple troughs of semi-cylindrical form in cross-section whereby the coins may be placed therein from the front and be at 110 all times exposed to view so that the operator may supply additional coins as those in the stacks are discharged, and opportunity is afforded him of observing the coins in the various stacks whereby the presence of a 115 coin in the wrong stack may be readily noted.

Each section of the coin stacks is under the control of one row or group of keys, but in the keyboard there are five groups or rows 120 of keys, the left hand row or group in the construction shown being a row or group which does not control a section of the coin stacks nor the discharge of coins, but it does control the operation of a type segment and 125 a registering wheel for printing and indicating large sums returned to a customer from an independent source of supply or

cashier's drawer. As illustrated, the first group of column to the right may be said to be a unit ~~section~~ and the keys correspond to amounts up to nine cents, inclusive; the second column or group from the right corresponds to amounts from ten cents to ninety cents, inclusive; the third column to amounts from one dollar to nine dollars, inclusive; the fourth column to amounts from ten dollars to ninety dollars, inclusive, and the fifth column to amounts from one hundred dollars to nine hundred dollars, inclusive.

The selector plates are interposed directly between the ends of the ejectors and the bases of the coin stacks or receptacles and apertures are arranged in the selector plates which correspond to the ejectors which are to be operated in accordance with the key designated. By this arrangement the mechanism is materially simplified and it becomes practicable to arrange the parts conveniently for purposes of manufacture and to produce a machine having a minimum number of parts capable of relative positioning with the ejectors and their selector plates or segments in immediate proximity to the bases of the coin stacks or holders while the key board etc. is located entirely at one end of the coin receptacles in convenient position for manipulation with one hand.

In the present machine it will be observed that the printing mechanism is correlated to the mechanism for delivering or controlling the delivery of the coins and is adapted for printing figures which correspond to the amount discharged.

The operation of the machine will be understood from the foregoing description without further detail mention of the movements of the various parts. It will be observed, however, that the arrangement of the keyboard, operating handle, printing mechanism, registering mechanism and coin stacks or receptacles, together with the ejectors and their controlling selector plates, is such as to enable the operator to handle the machine in a most expeditious manner, thus with his right hand he may operate the keys of the keyboard corresponding to the amount which he desired to have delivered by the machine, then, or simultaneously with the act of operating the keys he may place the check or receipt on the table in position to receive the impression of the type and immediately thereafter grasp the operating handle and impart the necessary forward and backward movements thereto for effecting the discharge of the coins, the printing of figures corresponding to the amount discharged and the registration of said amount in the registering devices. The hopper for the coin stacks or receptacles will conduct the coins down to a single position where they may be conveniently received in the

left hand or taken from the tray into which they drop.

Having thus described my invention what I claim as new is:—

1. In a coin delivering apparatus, the combination with a row of coin stacks or receptacles, a series of ejectors each movable in a path intersecting the base of one of the stacks, selector plates arranged side by side in proximity to and each governing the ejectors for a different section of the stacks, of a keyboard at one end of the row of stacks, a plurality of separate groups of keys each group governing the positioning of one selector plate only, an operating handle in proximity to the keyboard and connections intermediate said handle, selector plates and ejectors.

2. In a coin delivering apparatus, the combination with a row of coin stacks or receptacles, ejectors arranged in groups movable in paths intersecting the bases of the stacks, selector plates arranged side by side and each movable in a path intersecting one group only of the ejectors, of a keyboard at one end of the row of stacks, independent groups of separately operable keys in said keyboard each group governing the positioning of one selector plate only, an operating handle and connections intermediate said handle, selector plates and ejectors.

3. In a coin delivering apparatus, the combination with a row of coin stacks or receptacles arranged in groups, the stacks of each group being adapted to hold coins of different denominations, ejectors for ejecting the coins from the bases of the stacks arranged in groups corresponding to the groups of stacks, independently controlled means for independently selecting ejectors in each of the different groups which shall be operated to eject coins and for restraining the operation of the remaining ejectors, of a keyboard, a plurality of parallel groups of keys in said keyboard each group governing the selecting mechanism for a different group of ejectors independently of the selecting mechanism of the other groups, an operating handle and connections between said handle and ejectors of all the groups whereby the selected ejectors may be operated.

4. In a coin delivering apparatus, the combination with a row of coin stacks or receptacles arranged in groups, a keyboard located at one end of said row of receptacles, printing and registering mechanisms located in proximity to said keyboard, and a coin chute having inclined walls for receiving the coins from the receptacles and conducting them to a single point of delivery in front of and below the coin stacks, of ejecting mechanism located in proximity

to and in rear of the bases of the stacks, selecting mechanism also located in proximity to and in rear of the bases of the stacks, separate groups of keys in the keyboard, each group governing selecting mechanism for a different group of stacks, and an operating handle with operating connections between said handle and ejecting mechanism, said handle being located 10 at the side of the keyboard remote from the coin stacks.

5. In a coin delivering apparatus, the combination with the coin receptacle, ejectors movable in paths intersecting the bases 15 of the receptacles for discharging coin therefrom, selector plates each movable in a path intersecting the paths of certain of the ejectors not controlled by the other selector plates and having apertures therein 20 through which the selected ejectors may pass, of a keyboard embodying a plurality of groups of separately operated keys each group governing the positioning of each selector plate, and means for operating the 25 selector plates and ejectors.

6. In a coin delivering apparatus, the combination with the coin receptacles, ejectors movable in paths intersecting the coin receptacles for discharging coins therefrom, 30 an arc-shaped selector plate angularly movable in a path intermediate the ejectors and coin receptacles and having apertures therein through which the ejectors pass to engage the coins in the receptacles, a plurality of independently operable keys governing the 35 positioning of the selector plate, and operating means for the selector plate and ejectors.

7. In a coin delivering apparatus, the combination with the coin receptacles, ejectors 40 movable in paths intersecting the bases of the receptacles, arc-shaped selector plates movable in paths intermediate the ends of the ejectors and coin receptacles, said selector plates having apertures therein for the 45 passage of the ejectors for discharging coin from the receptacles, and means for moving the selector plates, of an operating mechanism for the ejectors embodying a handle and positive connections intermediate said 50 handle and ejectors whereby coin in the receptacles will be invariably ejected by the selected ejectors when the operating handle is moved.

8. In a coin delivering apparatus, the combination with the coin receptacles, reciprocatory ejectors movable in paths intersecting the coin receptacles, selector plates having apertures therein for the passage of the ejectors and key governed means for positioning the selector plates, of an ejector operating mechanism embodying an operating shaft, a lever moved by said shaft and connections intermediate the lever and ejectors embodying means whereby the ejectors are

5 moved positively in unison with the levers 6 when the said ejectors are in engagement with a coin and means whereby the levers may be advanced without the ejectors when no coin is to be discharged.

9. In a coin delivering apparatus, the 7 combination with the coin receptacle, reciprocatory ejectors movable in paths intersecting said receptacles to discharge coins therefrom, selector plates having apertures 75 therein for the ejectors and movable in paths intermediate the ends of the ejectors and coin receptacles, a plurality of keys governing the positioning of each selector plate, an operating shaft, connections between said 80 shaft and selectors and connections between said shaft and ejectors operable only after said shaft has partially completed its movement, whereby the selector plates are positioned before the ejectors are operated.

10. In a coin delivering apparatus, the 85 combination with the coin receptacles, ejectors movable in paths intersecting said receptacles to discharge coins therefrom, selector plates having apertures therein for the 90 passage of the ejectors and key-governed mechanism for controlling the positioning of the selector plates, of an operating shaft, connections intermediate said shaft and selector plates and connections intermediate said shaft and ejectors embodying a loose 95 connection whereby the shaft may partially complete its movement in one direction to position the selectors and complete its movement in the same direction to operate the ejectors.

11. In a coin delivering apparatus, the combination with the coin receptacles, ejectors movable in paths intersecting said receptacles to discharge coins therefrom, selector plates having apertures therein for 10 the passage of the ejectors and key-governed mechanism for controlling the positioning of the selector plates, of an operating shaft, connections intermediate said shaft and selector plates, and connections intermediate 11 said shaft and ejectors embodying a loose connection whereby the shaft may partially complete its movement to position the selectors before the ejectors are operated, a latch interposed in said connections for returning 11 the ejectors during the initial return movement of the operating shaft, and means for disengaging said latch.

12. In a coin delivering apparatus, the combination with the coin receptacles, ejectors movable in paths intersecting the said receptacles to discharge coins therefrom, selector plates movable in paths intersecting the paths of the ejectors and having apertures therein for the passage of the ejectors 12 whereby ejectors may be selected for discharging coins of the proper denomination and key controlled means for determining

- the positions of the selector plates, of an operating shaft, an arm keyed to said shaft, an ejector operating lever journaled on the shaft, a loose connection between said arm and lever whereby the shaft is permitted a limited independent movement, a latch for connecting the arm and lever at one extreme of their relative movement, and means for disengaging said latch.
13. In a coin delivering apparatus, the combination with the coin receptacles, ejectors movable in paths intersecting said receptacles for discharging coins therefrom, selector plates having apertures therein for determining which ejector shall be operative and key-governed means for determining the positions of the selector plates, of an ejector operating shaft, connections between said shaft and the selector plates for moving the latter, loose connections between the said shaft and ejectors, a link interposed in said connection, and means for positively connecting said link and ejectors for simultaneous movement while the ejectors are being advanced to discharge a coin.
14. In a coin delivering apparatus, the combination with the coin receptacles, ejectors for discharging coins therefrom and key governed selector plates having apertures whereby the desired ejectors may be controlled, of an ejector operating shaft, a lever arm moved by said shaft, a pawl interposed in the connections between said arm and ejectors, and means whereby said pawl may be moved into or out of its operative position to connect the arm and ejectors.
15. In a coin delivering apparatus, the combination with the coin receptacles, ejectors for ejecting coins therefrom and key governed selector plates for determining which ejector shall be operative to eject coin, an operating shaft, and connections between said shaft and ejectors embodying a yielding connection for inaugurating the movement of the ejectors, and a pawl connection for establishing a positive connection after the ejector movement is inaugurated, and means for disengaging said pawl when the ejectors are in normal inoperative position.
16. In a coin delivering apparatus, the combination with a plurality of coin receptacles, a plurality of ejectors movable in paths intersecting said receptacles to discharge coins therefrom, a plurality of selector plates movable in paths intersecting the paths of the ejectors, a plurality of shafts on which said plates are mounted side by side in position to coöperate with different ejectors, and operating mechanism for the ejectors, of operating arms for said selector plates mounted on the shafts in different planes longitudinally of the shafts and a plurality of positioning keys for co-operation with each of said arms to determine the positions to which the selector plates may be adjusted.
17. In a coin delivering apparatus, the combination with a plurality of coin receptacles, a corresponding plurality of ejectors, arc-shaped selector plates for determining which ejectors shall be operable to discharge coins from the receptacles, shafts on which said selector plates are mounted in different planes longitudinally of the shafts, and means for operating the ejectors, of control arms mounted on the selector plate shafts in different planes longitudinally of the shafts, and a group of keys for each arm independently operable to determine the position of the selector plate controlled thereby.
18. In a coin delivering apparatus, the combination with the coin receptacles, ejectors for discharging coins from the receptacles and means for operating said ejectors, of curved selector plates having openings therein through which the ejectors pass into engagement with the coins, shafts on which said selector plates are mounted in different planes longitudinally of the shafts whereby each selector plate governs a different set of ejectors, control arms also mounted on said shafts in different planes longitudinally of the shaft, independent groups of keys each key operable into a position to coöperate with the arm governed thereby, and means whereby the selector plates, shafts and arms may be moved into adjusted position preliminary to the operation of the ejectors.
19. In a coin delivering apparatus, the combination with a series of coin receptacles, ejectors for discharging coins from the receptacles, and means for operating said ejectors, of selector plates movable in paths intermediate the ends of the ejectors and coin receptacles, said selector plates being arranged side by side and each coöperating with a separate group of ejectors, operating shafts for said selector plates all extending beyond one end of the series of selector plates, a separate control arm connected with each of said shafts, said arms being located in different planes longitudinally of the shafts, a separate group of keys governing the positioning of each of said arms; and means whereby the arms and selector plates may be moved into adjusted position preliminary to the operation of the ejectors.
20. In a coin delivering apparatus, the combination with the coin receptacles arranged side by side, ejectors for discharging the coins from the receptacles and means for operating said ejectors, of selector plates arranged side by side in alinement with each other and each having ejector governing apertures whereby each selector plate

governs a separate group of ejectors, separate operating shafts for the selector plates all extending beyond one end of the series of plates, control arms located in different vertical planes and each connected with a selector plate shaft, a plurality of groups of separately operable keys, one group for each control arm, and means whereby the control arms and selector plates may be moved into adjusted position preliminary to the operation of the ejectors.

21. In a coin delivering apparatus, the combination with the coin receptacles arranged side by side, ejectors for ejecting coins from the receptacles and means for operating said ejectors, of selector plates governing the ejectors and arranged in line side by side, concentric shafts with which said selector plates are connected for operation, said shafts being of different length and extending beyond one end of the series of selector plates, a control arm connected with the end extension of each selector shaft, a plurality of groups of keys each group arranged in a different vertical plane, one group being provided for governing the operative position of each control arm, and means whereby the control arms and selector plates may be moved into adjusted position preliminary to the operation of the ejectors.

22. In a coin delivering apparatus, the combination with the coin receptacles, ejecting mechanism for discharging coins therefrom, selectors for determining which ejector shall be operative to eject coins from the receptacles, control arms for the selectors, groups of keys, one group for each control arm for governing the position of said arm and selector controlled thereby, and means for successively operating the control arms and ejectors, of a printing mechanism embodying type carriers one connected with each of the control arms and positioned thereby to bring a type face to the printing point in unison with the movement of the selector, an impression member for co-operating with the type at the printing point, and operating mechanism for said impression member intermediate the impression member and said means for operating the selectors and ejectors.

23. In a coin delivering apparatus, the combination with the coin receptacles, ejectors movable in paths intersecting the receptacles for discharging coins therefrom by direct engagement with the coins, said ejectors being arranged in groups, and key governed selector plates one for each group of ejectors for determining which ejectors shall be operative to eject coins from the receptacles, of a registering mechanism and operative connections between the registering mechanism and each of the selector plates whereby the positioning of the se-

lector plates registers the amount to be delivered by the ejectors.

24. In a coin delivering apparatus, the combination with the coin receptacles, ejectors movable in paths intersecting the receptacles for discharging coins therefrom by direct engagement with the coins, selector plates one for each group of ejectors for determining which ejectors shall be operative to eject coins from the receptacles, key governed control arms one for each of the selector plates, and means for moving said arms, of a registering mechanism and operating connections between said registering mechanism and each of the control arms whereby the positioning of the selector plates operates the registering mechanism to register the amount to be discharged by the ejectors.

25. In a coin delivering apparatus, the combination with the coin receptacles, ejectors for discharging coins therefrom, selector plates each for determining which ejectors shall be operative to eject coins from a different group of the receptacles, control arms connected with each of said selector plates, a group of keys for determining the operative positions of each of the control arms and a gear segment connected with said control arms, of a registering mechanism and operating connections between said registering mechanism and control arms embodying rack bars meshing with said gear segments whereby the positioning of the selector plates operates the registering mechanism to register the amount to be discharged by the ejectors.

26. In a coin delivering apparatus, the combination with the coin receptacles, ejectors for discharging coins therefrom, selector plates for determining which ejector shall be operative to eject coins from the receptacles and an operating handle for said ejectors, of a registering mechanism, connections intermediate said registering mechanism and selector plates whereby the registering mechanism will be operated simultaneously with the positioning of the selector plates to register the amount to be discharged by the ejectors, and connections between the ejector operating handle and registering mechanism for disconnecting said registering mechanism from the selector plates during the return of the selector plates to normal position.

27. In a coin delivering apparatus, the combination with the coin receptacles, ejectors for discharging coins therefrom, selector plates for determining which ejector shall be operative to eject coins from the receptacles, control arms connected with the selector plates, a group of keys for governing the operative positions of each of the control arms and an operating handle for

the ejectors, of a registering mechanism, operating connections intermediate said registering mechanism and control arms embodying rack bars and gear wheels movable into and out of mesh with said rack bars and connections intermediate said gear wheels and ejector operating handle whereby the registering mechanism will be disconnected from the selector plates during 10 the return movement of the ejectors.

28. In a coin delivering apparatus, the combination with the coin receptacles and a key board embodying separately operable keys, of a coin delivering mechanism embodying ejectors, selector plates controlling the ejectors, control arms for the selector plates, latches on said control arms for coöperation with the keys, an operating mechanism for the control arms, connections intermediate 20 said operating mechanism, arms and latches whereby the arms are moved and the latches held in locking positions when the movement of the arms is arrested, a handle for the operating mechanism and loose connections intermediate the handle and ejectors whereby the latter are moved only after the arms are locked.

29. In coin delivering apparatus, the combination with the coin receptacles and a key board embodying separately operable keys, of coin delivering mechanism embodying ejectors, selector plates controlling the ejectors, control arms connected with the selector plates, latches on the control arms for 35 locking the arms and keys together, an operating frame, driving connections intermediate the operating frame and control arms embodying pawls connected with the latches and coöperating with notches in the frame, 40 an operating shaft, loose connections intermediate said shaft and ejectors and direct connections intermediate said shaft and the operating frame whereby the operating frame will be moved and the selectors operated prior to the operation of the ejectors.

30. In a coin delivering apparatus, the combination with the coin receptacles and a key board embodying separately operable keys, of a coin delivering mechanism embodying control arms, locking mechanism for connecting said arms and keys, an operating frame for the arms, embodying disks with notches therein, pawls connected with the locking mechanisms adapted to enter said notches and concentric faces with which the pawls coöperate during the independent movement of the operating frame to maintain the locking connection between the arms and keys, substantially as described.

31. In coin delivering apparatus, the combination with coin receptacles and a key board embodying separately operable keys, of coin delivering mechanism embodying ejectors, selector plates controlling the ejec-

tors, control arms connected with said selector plates, locking mechanisms for connecting said arms and operated keys in the key board, and an operating mechanism embodying an oscillatory shaft, connections between said shaft and the ejectors and connections between said shaft and the control arms adapted to hold the locking mechanism between the keys and arms in locking position during the operation of the ejectors.

32. In a coin delivering apparatus, the combination with a keyboard embodying separate groups of independently operable keys, a plurality of independent selector plates, one controlled by each group of keys, and a plurality of ejectors controlled by each selector plate independently of other ejectors and selector plates, an operating handle independent connections intermediate the handle and each selector plate each connection being controlled only by the group of 85 keys for that selector plate, a delayed movement connection intermediate the operating handle and ejectors, and coin receptacles from which coins are discharged by the 90 ejectors.

33. In coin delivering apparatus, the combination with a keyboard embodying separate groups of independently operable keys, a plurality of shafts, a control arm on each shaft there being a control arm for each group of keys and all of said arms being movable in planes parallel with each other, and an independent selector plate connected with each shaft, said selector plates being arranged side by side and movable in planes 95 parallel with each other, of a plurality of ejectors controlled by each selector plate independently of the ejectors controlled by the other plates, an operating handle for the selector plates and ejectors and coin receptacles from which coins are discharged by the 100 ejectors.

34. In coin delivering apparatus, the combination with a keyboard embodying parallel groups of independently operable keys, 110 a plurality of shafts of different length, a control arm on one end of each shaft, said arms being movable in parallel planes, one in the plane of each group of keys, and a selector plate connected with the opposite end of each shaft, said selector plates being movable in parallel planes, of a plurality of ejectors controlled by each plate independently of the ejectors controlled by the other plates, an operating handle and coin receptacles from which coins are discharged by the 115 selected ejectors.

35. In coin delivering apparatus, the combination with a keyboard embodying parallel groups of independently operable keys, 120 a plurality of concentric shafts of different length, a control arm on one end of each shaft, said arms being movable one in the

plane of each group of keys, and a selector plate connected with the opposite end of each shaft, said selector plates being movable in parallel planes, of a plurality of 5 ejectors controlled by each plate independently of the ejectors controlled by the other plates, an operating handle and coin recep- tacles from which coins are discharged by the selected ejectors.
